UNITED STATES PATENT OFFICE.

VINCENT BENDIX, OF CHICAGO, ILLINOIS.

ENGINE STARTER.

Application filed March 28, 1921. Serial No. 456,096.

To all whom it may concern:

Be it known that I, VINCENT BENDIX, a citizen of the United States, residing at Chicago, in the county of Cook and State 5 of Illinois, have invented certain new and useful Improvements in Engine Starters, of which the following is a specification.

My invention has relation to engine starters for starting or cranking internal combustion engines, and the like, and more particularly to that part of the starter known as the drive or transmission for operatively connecting between the prime mover, such as an electric motor, and a part of the engine 10 to be started such as the flywheel thereof with which such drive is caused to engage. The object of my invention is to provide a simple and efficient form of drive which operates automatically for engagement purposes and for disengagement purposes either manually or automatically according to whichever of two types herein shown is employed. The various features 15 of advantage and utility in my construction of drive will be apparent from the description hereinafter given.

In the drawings, Fig. 1 is an elevation partly in section of an engine starter embodying one form of my invention; Figs. 2, 20 3 and 4 sections on the corresponding section lines of Fig. 1; Fig. 5 a view similar to Fig. 1 but illustrating a modification as to the location of the spring; Fig. 6 a view similar to Fig. 1 but illustrating another 25 form of construction; Fig. 7 a section on the line 7—7 of Fig. 6 and Fig. 8 a view similar to Fig. 6 but illustrating a form modified as to the location of the spring.

My invention may be embodied in different forms and types of drives without departing from the spirit of my invention. For instance while my invention is shown in connection with a drive of the direct or single reduction type and also of the inboard 40 type, it will be understood that my invention is applicable to the indirect or so-called double reduction type and also to the outboard type.

Referring to the particular embodiment 45 of my invention shown in Figs. 1 to 4, the starting motor 1 is provided with an extended armature shaft 2 whose outer end is journaled in the bearing 3. The driving member which is here a pinion 4 is mounted

on the shaft 2 for longitudinal movement 55 thereof and rotary movement therewith. In the present instance, the pinion is mounted to slide upon the longitudinal splines 5 of the shaft which splines engage the longitudinal internal grooves 6 in diametrical opposite sides of the interior of the bore of the pinion as shown in Fig. 2. This pinion when moved longitudinally to the left, Fig. 1, is adapted to mesh with the teeth 7 of the engine member which is here a flywheel 8. 65

The driving member or pinion is normally pressed with a yielding pressure (while in its normal position shown in full lines) in a direction toward the flywheel teeth but the same is restrained by an operating means 70 which is under the control of the operator. The yielding means which tends to force the pinion into mesh with the flywheel is a coiled spring 9 encircling the shaft 2 and bearing at one end against the outer or right hand end of the pinion and at its other end against the collar 10 which is secured to the shaft 2 in suitable manner as by the pin 11. When the pinion is in normal position as 75 shown in Fig. 1 this spring 9 is under compression and tends to force the pinion into mesh with the flywheel whenever the restraining influence, hereinafter described, is relieved, so that the spring can expand. 80

The means for controlling the action of 85 the spring 9 consists of an actuating rod or plunger 12 which here extends through the dashboard 13 of an automobile and more particularly through a hole 14 in a plate 15 which is fastened to such board. This rod 90 also has its bearing in a bracket 16 anchored to and extending inward from the dashboard. The inner end of the rod 12 is bifurcated so as to provide a shifting yoke 17 terminating in inturned rollers 18 which 95 are received within the circumferential groove 19 formed by the two circular flanges 20 at the outer end of the pinion 4. This rod 12 is detachably locked in its outward position in suitable manner. In the present 100 instance this locking means consists of a shoulder 21 on the upper side of the rod adapted to engage the upper side of the hole 14 and held thereagainst by means of the spring 22 bearing against the lower side of 105 the rod 12.

When the parts are in the normal position shown in Fig. 1, the rod 12 is held in its

outward position (shown in full lines) by said locking means and consequently the spring 9 which is in compressed condition, is prevented from expanding and from shifting the pinion into mesh with the flywheel. However, when the operator operates the rod 12 by depressing the handle 23 and thereby releases it from the lock, such rod will be moved inwardly by the expanding action of the spring 9, or both by the operator and spring. As a result, the pinion 4 will be moved automatically into mesh with the flywheel as shown in dotted lines in Fig. 1.

15 In the present instance, the rod 12 serves the additional purpose of actuating a switch for the current to the starting motor and the construction herein shown is preferably so arranged that the motor will begin to rotate and thereby start to rotate the pinion 4, just before the latter reaches the flywheel teeth, thereby assuring the proper meshing of the pinion teeth and the flywheel teeth.

Referring to the electrical switch details, 25 the bracket 16 is provided with the two electrical contacts 24 which are arranged parallel to each other and in the path of movement of a connector 25 secured to and extending upwardly from the rod 12 and 30 adapted to have a wiping contact between the two contacts 24. These contacts are electrically connected by the wires 26—26 with the motor 1.

Describing a cycle of operation and starting with the parts in their normal position shown in Fig. 1, the operator merely depresses the handle 23, thereby unlocking the rod 12 and permitting the spring 9 to shift the rod inwardly and consequently to 40 shift the pinion 4 to the left into mesh with the flywheel teeth. However, just before the pinion reaches the flywheel teeth, the connector 25 will close the motor circuit and start the motor and its shaft into rotation, 45 thereby facilitating the meshing of the pinion teeth and the flywheel teeth. The flywheel will now be rotated and when the engine starts on its own power, the operator will draw the rod 12 outwardly, thereby 50 compressing the spring 9 so as to be in condition for the next starting operation. At the same time, the rod 12 will be locked in its outward position and held locked by the spring 22.

55 In Fig. 5 I have shown a modified form of construction which is the same as Fig. 1 with the exception that the spring 27 which has the same function as the spring 9, is associated with and located on the rod 12 instead of encircling the shaft 2. The operation of the spring in this changed location is the same as before.

In Figs. 6 and 7, I have shown a modified form of construction which differs from 65 that previously described more particularly

in the provision of means for automatically demeshing the pinion from the flywheel. In this construction, the corresponding parts are given the same reference numerals. The shaft 2 instead of being a plain shaft provided with a spline at its inner end is provided with screw threads 28 at such inner end and the pinion 4 is threaded thereon. As a result, when the pinion 4 is moved inwardly by the action of the spring 9 in 75 the manner hereinbefore described, the pinion 4 is slightly rotated by the cooperation of its threads with the screw shaft thereby facilitating the meshing of the pinion teeth and the flywheel teeth. Nevertheless, I prefer to turn the current on to the motor before initial engagement of these teeth occurs. When the engine has started on its own power the pinion 4 is automatically demeshed by reason of the excess speed of rotation imparted to the pinion by the flywheel whereupon such pinion 4 is moved longitudinally to the right against the pressure of the spring 9. The rod 12 is likewise shifted to the right and when such rod reaches its normal position, the locking means operates to hold it in said position as shown in Fig. 6.

The construction shown in Fig. 8 is the same as that of Fig. 6 with the exception of the location of the spring 29 which is here associated directly with the rod 12 instead of directly with the shaft 2. However, the general action of this modified form is the same as that above described.

The specific construction illustrated in Fig. 6 is made the subject-matter of a pending application filed on April 6, 1921, Serial No. 459,037.

I claim:

1. An engine starter drive including a rotatable shaft, a driving member mounted thereon for longitudinal movement thereof and rotary movement therewith, means tending to shift the driving member longitudinally into engagement with a member of the engine to be started, and mechanism for restraining such means and for withdrawing the driving member from its engagement and into normal position.

2. An engine starter drive including a rotatable shaft, a driving member mounted thereon for longitudinal movement thereof and rotary movement therewith, means tending to shift the driving member longitudinally into engagement with a member of the engine to be started, and a rod engaging the driving member and adapted to hold the same in normal position against the shifting action of said means and to withdraw the driving member from its said engagement.

3. An engine starter drive including a rotatable shaft, a driving member mounted thereon for longitudinal movement thereof

- and rotary movement therewith, means tending to shift the driving member longitudinally into engagement with a member of the engine to be started, said driving member having a circumferential groove and a rod having a yoke engaging the groove and adapted to hold the driving member in normal position against the shifting action of said means and to withdraw the driving member from its said engagement. 4. An engine starter drive including a rotatable shaft, a driving member mounted thereon for longitudinal movement thereof and rotary movement therewith, means tending to shift the driving member longitudinally into engagement with a member of the engine to be started, a rod engaging the driving member and adapted to hold the same in normal position against the shifting action of said means and to withdraw the driving member from its said engagement, and a locking device for said rod comprising a stationary plate through which the rod passes and which engages said rod when in normal position. 5. An engine starter drive including a rotatable shaft, a driving member mounted thereon for longitudinal movement thereof and rotary movement therewith, means tending to shift the driving member longitudinally into engagement with a member of the engine to be started, a rod engaging the driving member and adapted to hold the same in normal position against the shifting action of said means, and a locking device for said rod comprising a stationary plate having a hole through which the rod passes, such rod having a notch on one side to engage a side of the hole, and a spring for pressing such notch against said side. 6. An engine starter drive including a rotatable shaft, a driving member mounted thereon for longitudinal movement thereof and rotary movement therewith, a compression spring encircling the shaft and acting on the driving member to shift it into engagement with a member of the engine to be started, and mechanism for restraining such action of the spring, such mechanism comprising a manually controlled rod engaging the driving member and adapted to hold it in normal position against the pressure of said spring and to withdraw the driving member from its said engagement. 7. An engine starter drive including a rotatable shaft, a driving member mounted thereon for longitudinal movement thereof and rotary movement therewith, means tending to shift the driving member longitudinally into engagement with a member of the engine to be started, mechanism for restraining such means, an electric motor for rotating the shaft, and a switch governing the current to the motor and controlled by such mechanism. 8. An engine starter drive including a rotatable shaft, a driving member mounted thereon for longitudinal movement thereof and rotary movement therewith, means tending to shift the driving member longitudinally into engagement with a member of the engine to be started, mechanism for restraining such means, an electric motor for rotating the shaft and a switch governing the current to the motor and under the control of such mechanism for admitting current to the motor just prior to initial engagement of the driving member and the engine member. 9. An engine starter drive including a rotatable shaft, a driving member mounted thereon for longitudinal movement thereof and rotary movement therewith, means tending to shift the driving member longitudinally into engagement with a member of the engine to be started, a reciprocating rod engaging the driving member and adapted to hold the same in normal position against the shifting action of said means, an electric motor for rotating the shaft, and a switch governing the current to the motor and controlled by the rod in its reciprocations. 10. An engine starter drive including a rotatable shaft, a driving member mounted thereon for longitudinal movement thereof and rotary movement therewith, means tending to shift the driving member longitudinally into engagement with a member of the engine to be started, a reciprocating rod engaging the driving member and adapted to hold the same in normal position against the shifting action of said means, an electric motor for rotating the shaft, a switch governing the current to the motor and having a pair of contacts, and a connector mounted on the rod and adapted to connect the contacts. 11. An engine starter drive including a rotatable shaft, a driving member mounted thereon for longitudinal movement thereof and rotary movement therewith, means tending to shift the driving member longitudinally into engagement with a member of the engine to be started, a reciprocating rod engaging the driving member and adapted to hold the same in normal position against the shifting action of said means, an electric motor for rotating the shaft, a switch governing the current to the motor and having a pair of contacts, and a connector mounted on the rod and adapted to connect the contacts, said connector being so located on the rod that it will connect the contacts and start the motor before initial contact of the two members.
